UNITED STATES PATENT OFFICE.

JOHN A. COLEMAN, OF PROVIDENCE, RHODE ISLAND.

MACHINE FOR MAKING HORSESHOE-NAILS.

SPECIFICATION forming part of Letters Patent No. 244,188, dated July 12, 1881.

Application filed April 14, 1881. (No model.) Patented in England December 9, 1880.

To all whom it may concern:

Be it known that I, JOHN ADDISON COLEMAN, a citizen of the United States, residing at Providence, county of Providence and State of Rhode Island, have invented a new and useful Improved Machine for the Manufacture of Nails for Fastening Horseshoes and other Purposes, (for which I have obtained a patent in Great Britain, No. 5,151, bearing date December 9, 1880,) of which the following is a specification.

It has been proposed to manufacture nails such as are employed for fastening horseshoes by machinery operating in the following manner: A bar of iron rolled with a thickened rib along each edge is fed, step by step, under a pair of punches, which by their descent punch transversely therefrom two blanks or pieces of the metal, intended each to form a nail, the thickened end in each case being suited to form the head of the nail. As these pieces are severed they lie to opposite hands in the die, and in that position they are received by spring-fingers, which, by a sweeping movement, take them out of the die and carry them round, one toward the right and one toward the left, and insert them between two rollers. In passing through between those rollers the blanks are drawn out in length and squeezed partly toward the finished shape. Leaving the rollers, the blanks are again seized by fingers and transferred to another pair of rollers, by which they are further drawn and pointed to the required shape. From the second pair of rollers the nails are transferred to a pair of finishing-punches, which strip off the thin fins and such other protuberances as may be caused by the squeezing action of the rolls, delivering the nails in finished condition.

My invention consists in improvements in the general arrangement and construction of apparatus of this kind, whereby the structure and action of the parts are rendered more simple, and the machine, besides being less expensive in first cost, is thus rendered more durable and capable of producing an increased quantity of the articles which it manufactures.

The accompanying drawings represent my improved machine.

Figure 1 is a front view, Fig. 2 a side view, and Fig. 3 a vertical section, of the machine.

The other figures show separately parts thereof drawn to an enlarged scale—that is to say, Fig. 4 is a front view, Fig. 5 a side view, and Fig. 6 a plan, of the apparatus for transferring the punched blanks from the die to the first pair of squeezing-rollers. Fig. 7 is a front view, showing the mode of holding the blank as it issues from the first pair of rolls so as to transfer it to the second pair of rolls, Fig. 8 being an enlarged side view, and Fig. 9 an enlarged plan, of the spring-holders employed for this purpose. Figs. 10 and 11 are respectively front and side views, showing the mode of holding the nails ready for the action of the finishing-dies.

In all these figures corresponding parts are marked by similar reference-letters.

A is the framing of the machine, which at its upper part has bearings for the main shaft A', by the continued revolution of which all the movements of the various parts are effected. This shaft may conveniently be driven, as shown, by bevel-gearing A² A³ from a more rapidly revolving shaft, A⁴, which may be driven from any suitable motor. In the middle of the shaft A is fixed an eccentric, A⁵, which in every revolution of the shaft gives an up-and-down motion to a pair of punches, b. These punches are so shaped as to punch at each stroke a pair of blanks having approximately the shape of the nails from a bar, B. This bar, as is more clearly seen in Fig. 4, is rolled of a section having the metal thickened toward each edge, and the two punches b being set, the one with the broad part of its face toward the right and the other with the broad part of its face toward the left, each punches out a blank having one of its ends wider and thicker than the other to form the nail-head, the two blanks thus punched being forced through the die b' with their heads presented toward the right and left, respectively. At each upstroke of the punches b the bar B is fed forward a suitable distance to present fresh metal for the next punching. This feed-motion is effected in the following manner: A barrel-cam, A⁶, on the shaft A gives a reciprocating movement to a bent lever, B', and through it to a sliding carriage, B². In this carriage is a hinged flap, b², which is alternately pressed firmly down on the bar B and relieved therefrom. This move-

ment is effected by a face-cam, A⁷, on the shaft A, which, engaging a stud on a vertical slide-bar, a, causes it to reciprocate, and this movement, communicated by a connecting-rod, a', to 5 a lever, a², mounted on the carriage B², brings a cam-face, a³, on that lever alternately to bear on the flap b² and to relieve it. The cams A⁶ and A⁷ are so timed to one another and to the eccentric A⁵ that while the punches b, worked 10 by A⁵, are performing the upper part of their movement clear of the bar B the flap b² is pressed firmly on the bar B and the carriage B² is advanced the proper feeding distance. While the punches b descend the carriage B², 15 holding the bar B, remains stationary, and while the punches b are penetrating and holding the bar B the flap b² is released and the carriage B² moves back without tending to drag back the bar B. The two blanks punched 20 from the bar B are pressed through the die b', each in a horizontal attitude, being received between the spring-jaws of a holder, c', for the one blank and c² for the other blank. These two holders c' and c² are respectively fixed on 25 spindles C' and C², which are geared together by toothed wheels c³ and c⁴ at their ends, so that the two spindles make a partial revolution in opposite directions, the one of them, C', being worked by a crank which engages in a 30 cam-slot in a reciprocating plate, C³. This plate, which is mounted on a pivot, c⁵, is worked by a rod, C⁴, from a lever, C⁵, which is pivoted at C⁶, and has a forked end embracing an eccentric, A⁸, on the shaft A. The spindles C' 35 and C² are mounted on a frame, C, which is pivoted at c⁶ to the framing of the machine, and is drawn up by a spring, c⁷.

The cam-slot in C³ is so shaped as to give to the holders c' c² the following series of movements: First, having remained in their upper position for a time stationary, to receive their respective blanks pushed into them by the descent of the punches b, they are caused by the 40 partial movement of the lever C⁵ to turn through an angle of ninety degrees, each therefore turning its blank from a horizontal to a vertical attitude, with its head presented downward. The 45 crank of c' now comes against a stop, c⁸, on the frame C, preventing the holders c' c² from turning farther round; but the continued movement of C³ causes the frame C to move bodily downward, and the blanks are thus thrust by their 50 holders between the first pair of rollers, D' D². The dotted lines in Fig. 4 indicate these movements of the holders. As the lever C⁵ makes its back-stroke the frame C is raised by the spring c⁷ and the spindles C' C² are turned backward through ninety degrees, so that the 55 holders c' c² resume their first position, ready to receive another pair of blanks from the die b'.

The two pairs of rollers—D' D², the upper pair, and D³ D⁴, the lower pair—receive reciprocating rotary motion through a part of a revolution, each pair in opposite directions, by toothed 60 wheels D⁵ and D⁶, which gear with one another, while D⁵ gears with a pinion on the axis of the roller D', and D⁶ gears with a pinion on the

axis of D³, the pinion on D' gearing with a pinion on D², and the pinion on D³ gearing with a pinion on D⁴. The first wheel, D⁵, has on its 70 axis a crank-arm, D⁷, which is linked by a rod, D⁸, to a crank-pin, A⁹, projecting from the shaft A², so that for each revolution of the shaft A the rollers are caused to perform their complete reciprocation. The rollers have portions of their peripheries hollowed out, as indicated by the dotted lines d' d² in Fig. 4 and by the darkened parts d' d² d³ d⁴ in Fig. 3, these hollows being so shaped that the blanks delivered from the holders c' c² in between the rollers D' D² are, by the movement of these rollers, to a certain extent squeezed into shape and extended in length, and that the blanks, delivered thus partly shaped from the rollers D' D², are further shaped to their final form by the 80 hollows of the second pair of rollers, D³ D⁴, between which they are caused to pass. The rollers D' D² are so set on their axes, and their movement is so timed to that of the holders c' c², that they present their hollows d' d² upward when the holders c' c² descend, inserting the blanks between the rollers, and this descending movement of the holders is made to correspond as nearly as possible with the surface movement of the rollers D' D² as they begin to gripe the blanks, until the rollers, having got a firm gripe, drag the blanks out of the holders and pass them through to other holders ready to receive them below the rollers D' D², in order to transfer them to the lower rollers, D³ D⁴. The holders for this purpose (shown to an enlarged scale in Figs. 8 and 9 and appearing, partly in section, as they hold the blank in Fig. 7) present trumpet-mouthed slots having one side covered by a movable piece, 90 e', which is held up by a spring, e². The upper rollers, D' D², in delivering the two blanks from between them through a fixed guide, d⁵, thrust the blanks, head downward, one into each of the slots in e, the cover-piece e' yielding to let the heads of the blanks pass, and then being returned by the spring e², so as to gripe firmly the shanks of the blanks, the heads of the latter projecting below, as indicated in Fig. 7. The 100 blanks thus held in the slots of e are, by the descent of e, conveyed to the lower rolls, D³ D⁴, and have their heads thrust into the hollows of these rolls, which are at that time directed upward to receive them. The rolls D³ D⁴, having gripped the blanks, drag them out of the 110 holder e, which reascends to receive a succeeding pair. As the blanks leave the rolls D³ D⁴ they are in a similar manner received by another holder like e, and are by it conveyed down to grippers hereinafter to be described, 115 by which they are presented to the finishing-punches.

The two holders—namely, e—above the rolls D³ D⁴ and the corresponding holder below these rolls are respectively at the ends of arms e³ 130 and e⁵, projecting from vertical rods e⁴ and e⁶. These rods are caused to reciprocate in a guide, E, respectively, by studs on them engaging in the cam-slots of two vibrating plates, E' and

E², worked by crank-arms E³ and E⁴ and connecting-rods E⁵ and E⁶ from two eccentrics, A¹⁰ and A¹¹, fixed side by side on the shaft A. The cam-slots in E¹ and E² and the eccentrics 5 which work these are so shaped and timed as to give the respective holders the required movements—that is to say, each remains for a time stationary in its highest position while it receives the blanks passed into its slots from the rolls above it. Then each descends to deliver the blanks, the one to the rolls D³ D⁴ and the other to the grippers, which will now be described.

A lever, F, pivoted at f', has the end of its 15 short arm rounded and toothed to gear with a short lever which is pivoted at f''. On each of the levers is a pair of fingers, having their upper ends shaped to receive and hold the heads of the nails. One of the fingers is in 20 each case fixed on its lever, the other being pivoted loosely thereon, and the fixed finger of each is linked to the movable finger of the other, so that as the lever F is caused to reciprocate the fingers of each pair are made to 25 open apart to receive a nail and to close together and gripe it. The lever F is worked by a link, F', from a sliding rod, F'', which is drawn up by a spring, F³. A projection, F⁴, on the rod F'' is struck by a spring-pawl hinged at 30 the end of an arm, E⁷, projecting from the axis of E⁴, so that when the holder worked by E² descends with the nails received from the lowest pair of rolls the grippers connected to F are opened for a moment to receive the nail-heads, 35 and when the arm E⁷ passes F⁴ the grippers are closed by the spring F³, so as to gripe tightly the nails g' g², which have been introduced between them. On the reascent of the arm E⁷ the spring-pawl at its end yields in 40 passing the projection F⁴. The nails g' g² are held by the grippers exactly in front of a die, G, having two holes through it, each exactly the shape of a finished nail, each hole receiving a punch, h, of the same shape. The punches 45 h are fixed to the face of a horizontal slide, H, which is connected by a link, H', to one arm, H², of a bell-crank lever, the other arm of which is connected by a rod, H³, to an eccentric, A¹², on the shaft A. By means of the punches h, 50 which at their forward stroke push the nails g' g² out of the grippers and through the die G, is performed the final operation of cutting off from the nails such fins, burrs, or projections of the metal as may have been produced by 55 the squeezing of the rolls, and the finished nails drop through a passage, G', behind the die G, the burrs sliced off by the punches and dies falling through an opening, G², in front of the die.

60 Although I have thus described an entire machine for manufacturing horseshoe or other nails by punching blanks from a bar of metal,

squeezing these blanks by rolls, and finishing them by final punching, I would have it understood that I make no general claim to this 65 system of manufacturing nails, nor to the described sequence of operations for that purpose, as a machine embodying these has been previously described in the patent-specification of L. W. Whipple, No. 228,792, dated 15th 70 of June, 1880; nor do I claim such of the mechanical details as are similar to those described in the said specification; but I only claim improvements in the construction and arrangement of a machine operating in this manner, 75 as follows:

I claim—

1. The herein-described machine with the framing A, having in its upper part bearings for the main shaft A', from which single shaft, 80 by means of cranks, eccentrics, and cams, the required movements are given to the feeding apparatus B² and b², to the punches b, to the blank-holders c' c², to the rolls D' D² D³ D⁴, to the two sets of holders e, the grippers of the 85 nails g' g², and to the finishing-punches h, all of said parts being combined, organized, and arranged to operate as shown and described.

2. The combination of the cams A⁶ and A⁷, the lever B' and slide B², the rods a a', lever 90 a'', and its cam-face a³, constituting the feed apparatus, substantially as herein described.

3. The combination of the eccentric A⁸, fork-lever C⁵ and rod C⁴, cam-slotted plate C³, spring-frame C, and holders c' c², for transferring the punched blanks from the die to the upper rolls, substantially as herein described. 95

4. The combination of the eccentrics A¹⁰ and A¹¹, their rods E⁵ and E⁶, the arms E² E³, the cam-slotted plates E' and E², and the slide-rods 100 e⁴ and e⁶, with spring-holders e, for transferring the blanks from the first pair of rolls to the second pair and from the second pair to the grippers, substantially as herein described.

5. The combination of the arm E⁷ and its 105 spring-pawl with the spring-slide F² and rod F', the lever F, and the grippers for holding the nails g' g² at the finishing-dies, substantially as herein described.

6. The method, substantially as herein described, of transferring a pair of punched blanks handed from a die to squeezing-rolls by causing them to turn through an arc of ninety degrees in opposite directions and then to advance to the gap of the rolls. 110

In testimony whereof I have signed my name to this specification, in the presence of two subscribing witnesses, this 30th day of March, A. D. 1881.

J. A. COLEMAN.
